UNITED STATES PATENT OFFICE.

GUSTAVE E. VILLARET, OF LEONIA, NEW JERSEY, ASSIGNOR TO SCOVILL MANUFACTURING COMPANY, OF WATERBURY, CONNECTICUT, A CORPORATION OF CONNECTICUT.

DESIGN FOR A CANOPY FOR LIGHTING FIXTURES.

Application filed July 8, 1927. Serial No. 22,702. Term of patent 7 years.

To all whom it may concern:

Be it known that I, GUSTAVE E. VILLARET, a citizen of the United States, residing at Leonia, county of Bergen, and State of New Jersey, have invented a new, original, and ornamental Design for a Canopy for Lighting Fixtures, of which the following is a specification, reference being had to the accompanying drawing, forming part thereof.

In the drawing Figure 1 is an elevation of a canopy showing my new design.

Fig. 2 is a plan of the same, and

Fig. 3 is a section on line 3—3, line 1.

I claim:

The ornamental design for a canopy for lighting fixtures, as shown.
